CONTROL SWITCH FOR HEAD LAMPS AND OTHER DEVICES

Homer F. Malone, Millburn, N. J., assignor to The Wilcolator Company, Elizabeth, N. J., a corporation of Delaware

Application September 25, 1952, Serial No. 311,461

18 Claims. (Cl. 200—113)

1

This invention relates to improvements in control switches for vehicle headlights and other electrical systems. More particularly, the invention relates to a rotary electric switch which includes means for protecting vehicle headlights from current overloads.

The primary object of the present invention is to provide an improved rotary headlight switch for vehicles in which the individual headlight, tail light, parking light, and other light circuits are protected by circuit breakers.

A further object of the invention is to provide a switch construction in which relatively simple parts are utilized which can be readily and quickly assembled.

Accordingly, the improved rotary electric switch of the present invention comprises a base member of insulating material having a plurality of contacts arranged on the front of the base member and electrically connected through the base, as for example, by means of rivets, to corresponding terminals mounted on or in the back of the base to which the wires of the vehicle lighting system, accessories and a wire from the current source are connected.

In one form of construction a metal plate is mounted on the front of the base member in fixed position over the contact connected to the power source and this plate carries a bimetal blade electrically connected thereto and having a movable contact normally engaging the contact over which the plate is mounted. A rotatable metal plate is mounted over the fixed metal plate and electrically connected thereto. These plates may be circular or dish shaped with their rims engaging each other. A plurality of bimetal blades are fixed to the back of the rotatable metal plate, each having a movable contact normally biased toward the front of the base member and adapted to engage selected ones of the contacts mounted on the front of the base member upon rotation of the rotatable metal plate.

This form of the switch advantageously includes a casing or cover provided with an axially arranged shaft and which is attached to the base member over the metal plates referred to above. The shaft inside the casing is arranged to rotate one or more driving members, for example a driving disc of insulating material which is keyed to the rotatable metal plate.

In a somewhat more simplified form of construction, the fixed and rotatable metal plates are eliminated and a single bimetal blade is mounted in the base member in fixed position and provided with a connection for the supply of cur-

2

rent to the switch. The base member, which is made of insulating material, also includes contacts in the front of the base connected to terminals arranged at the back of the base for connection to the various lighting circuits of the vehicle or accessories to which electric current is to be supplied. In this construction, the bimetal blade has a movable contact normally connected to certain of the terminals at the back of the base member. A rotatable disc of insulating material is carried inside the body of the switch structure and provided with contacts adapted to engage the contacts at the front of the base member. Connections are provided from the connector for the current source to a pair of bimetal blades carried on the rotatable disc and fixed thereto in a manner to protect the circuits made by its contacts. The rotatable disc is actuated by a driving member carried by a shaft extending through the front of the casing of the switch.

While in the two forms of construction referred to means is provided for rotating a member carrying a pair of bimetal blades, it is to be understood that the rotatable plate or disc in the switch may carry a single bimetal blade, while a pair of fixed bimetal blades may be mounted in the base member for the switch.

I have found that the switch of the present invention has the advantage that each of the separate circuits are protected against overloading. For example, if the circuit to one set of lights, such as the tail lights, is grounded, there can be no danger of overheating the wiring and possible resultant fires because the circuit breaker opens and closes automatically and limits the current feeding into the ground to a value which the wire can safely carry. Thus it may be possible to have intermittent light through the faulty circuit and proceed cautiously until an opportunity for repair is afforded.

The detailed features of my invention are described hereinafter in connection with two illustrative embodiments thereof shown in the accompanying drawings forming a part of this application.

In the drawings:

Figs. 1, 2, and 3 are front, side and back elevational views of one form of switch constructed in accordance with the invention;

Fig. 4 is an exploded elevational view showing the different principal elements of the switch shown in Figs. 1 to 3;

Fig. 5 is a vertical sectional view of the switch shown in Figs. 1 to 4;

Figs. 6 to 10 are elevational views of different elements of the switch, as shown in Fig. 4, Figs. 6 to 9 being back views and Fig 10 a front view;

Figs. 11, 12, and 13 are elevational views showing different positions for the movable contacts and switch elements associated therewith, of the switch shown in Figs. 1 to 10;

Figs. 14, 15 and 16 are respectively front, side and back elevational views of a second form of switch constructed in accordance with the present invention;

Fig. 17 is an exploded elevational view of the switch shown in Figs. 14, 15 and 16, showing the different principal elements;

Figs. 18, 19 and 20 are elevational views respectively of the front and back of the rotary member of the switch and of the front of the base of the switch shown in Figs. 14 to 17;

Fig. 21 is a vertical sectional view through the switch shown in Figs. 14 to 20; and

Figs. 22, 23 and 24 are elevational views partly in section showing the different positions of the rotary member of the switch with respect to the base of the switch shown in Figs. 14 to 21.

Referring to Figs. 1 to 5 of the drawings, the rotary switch therein shown comprises a metal cup-shaped cover 15 provided with an axially extending bushing 16 threaded at its free end, as shown in Fig 5, for receiving a nut by which the switch is mounted under a vehicle panel. The switch is operated by a shaft 17 extending through the bushing 16. The cover 15 at its front includes radially extending projections forming internal detent slots 18 for receiving a detent boss 19 carried on a spring detent member 20 staked to the inner end of the shaft 17. The peripheral portion of the cover 15 includes an enlarged cylindrical portion 21 providing a shoulder upon which the peripheral edge of a base 22 rests and on which it is retained by bentover tabs 23.

A metal driving plate 24 is staked onto the inner end of the shaft 17, along with the spring detent member 20, at approximately the angular relationship shown in Fig. 6. The driving plate 24 is provided with pressed-out lugs 25, which engage in matching slots 26 (Fig. 7) of a driving disc 27. The driving disc 27 is made of insulating material and bears against a rotatable dish-shaped metal plate 28 provided with pressed-out projecting lugs 29 engaging in peripheral matching slots 30 of the driving disc 27 (Figs. 7 and 5). The plate 28 on its side opposite the driving disc 27 carries two bimetal blades 31 and 32 electrically connected to the plate 28 and mounted in fixed positions thereon by rivets 33, as shown in Fig. 8.

The base 22 is made of insulating material and includes a peripheral rim projection 34 which fits in the portion 21 of the cover 15. The base 22 also includes a cylindrical wall section 35, which fits inside the cylindrical body portion of the cover 15, as shown in Fig. 5. The front portion of the base 22 is provided with an inside rectangular-shaped recess 36, shown in Figs. 5 and 10, the surface of which includes a contact 37 riveted to the base by a rivet 38 which also retains an accessory circuit "A" terminal 39. The back of the base 22 also carries terminals 41, 42, and 43, respectively for "H" head lights, "P" parking lights and "T" tail lights, held respectively by rivets 44, 45, and 46 (Fig. 3), which extend through the insulating material of the base and terminate in contacts 47, 48 and 49, respectively (Fig. 10). The rivet 46 is con-

nected by a metal jumper plate 50 with a rivet 51 (Fig. 3), extending through the material of the base 22 and terminating in a contact 52 (Fig. 10). The respective contacts referred to 5 are shown more completely in Fig. 10, and it will be seen from Figs. 5 and 10 that the contacts 41 to 49, and 52 are mounted in raised sections of insulation 53, so that the surfaces of these contacts are above the main body of the base 22.

The rim of the cylindrical portion 35 of the base 22 is provided with diametrically opposite projections 54, which serve as stops for limiting the rotary movement of the driving disc 27. The larger diameter portions of the disc 27 (Fig. 7) rest upon the rim of the cylindrical portion 35 and the stops 54 are engaged by the surfaces 55 of the driving disc 27.

A dish-shaped metal plate 56 is mounted in the cylindrical portion 35 of the base 22 with its peripheral flange engaging the peripheral flange of the metal mounting plate 23 (Fig. 5).

The back of the metal plate 56, facing the base 22, is shown in Fig. 9, from which it will be noted that it includes a pair of oblong-shaped openings 57 which fit over the correspondingly shaped pieces of insulation 53, shown in Fig. 10. A bimetal blade 58 is mounted on the back of the plate 56 by means of a rivet 59, and the plate 56 includes three openings 60 for receiving rivets 61 for securing the plate 56 firmly to the base 22 and forcing the movable contact 58' of the bimetal blade 58 into engagement with the contact 37 in the manner shown in Fig. 5, it being noted that the bimetal blade 58 fits in the rectangular-shaped recess 36 in the base 22. The metal plate 56 is pressed from the back to provide two circular-shaped depressions which provide contact surfaces 62 and 63 in the same plane and arc as the contacts 47, 48, 49, and 52.

The bimetal blades 31, 32, and 58 are similar in construction and each includes a U-shaped slot 64 forming a tongue 65 extending from the end portion of the blade opposite the rivet, which secures it to the metal plate. The tongues 65 carry contacts 66, 66' and 58', respectively. The legs of the bimetal blades are stiffened by oppositely arranged pressed-in elongated projections 67, respectively on opposite sides of the mounting rivet and overlapping the curved end of the U-shaped slot 64. The blade is prestressed by the drawing in of the legs of the blade at the place where it is mounted by the mounting rivet. The stress in the blade forces its free end against or adjacent to the plate on which it is mounted, while the contact and tongue extend forward from the plane of the blade under normal temperature conditions. The mounting end of the bimetal blade is pressed out toward the back in drawing the legs in, so that the main body of the blade is spaced away from the mounting plate, except at the position of the rivet. When an overload of current flows through one of the blades, it becomes heated and bows in the opposite direction, so that the contact is snapped away from the fixed contact, 37 for example, and breaks the circuit.

The metal plate 56 may be held in fixed position in the base by the rivets 61, so that the contact 58' of the bimetal blade 58 engages the contact 37, and/or by a terminal bolt 70 for supplying electric current to the switch, from the battery of the vehicle for example. The bolt 70 extends through a hole 71 in plate 56 and through 75 the base 22 to which it is held by a lock washer

and nut 72. A second nut 73 is provided for connecting a battery terminal. Electric current supplied through bolt 70 to the plate 56 is distributed to the bimetal blade 58, to the rotatable metal plate 28 and to the bimetal blades 31 and 32. The contact 66 of the blade 31 is adapted to engage the contacts 49 and 52, which are spaced and insulated from the plate 56, and also the contact surface 63, while the contact 66' is adapted to engage the contacts 47 and 48 and also the contact surface 62.

Figs. 11, 12, and 13 show three different positions of the driving disc 27 and the driven rotatable plate 28 with respect to the contacts shown in Fig. 10 and the contact surfaces 62 and 63 shown in Figs. 5 and 9. In Fig. 13 the contacts 66 and 66' of the bimetal blades 31 and 32 are out of engagement with any of the contacts shown in Fig. 10, but they are resting on the pressed-out contact surfaces 63 and 62, respectively of the plate 56, so that no current is flowing through blades 31 and 32. This is the off position of the switch, and under this condition, the bimetal blade 58 protects the accessory circuit or circuits.

If the shaft 17 is rotated one step in a clockwise direction to the second or first "on" position, the respective positions of the bimetal blades 31 and 32 and their contacts are as shown in Fig. 12. In this position, the contact 66 of the blade 31 supplies current to the contact 52, while the contact 66' supplies current to the contact 48, the respective terminals 43 and 42 of these contacts being connected to the tail lights and the parking lights, respectively of the vehicle. Contact 52 is connected to the terminal 43 by the jumper plate 50. The further rotation of the plate 28 in a clockwise direction to the third position moves it to the position shown in Fig. 11, in which the contact 66 of the bimetal blade 31 engages the contact 49, while the contact 66' of the bimetal plate 32 engages the contact 47. Since the contacts 49 and 52 are interconnected by the metal jumper 50, the contact 49 and terminal 43 connected therewith continue the supply of current to the tail lights of the automobile or other vehicle. Current supplied to the contact 47 is sent to the terminal 41 and to the "high" or driving lights of the vehicle.

In constructing the switch, the contacts 47, 48, 49, 52 and the contact surfaces 62 and 63 are arranged in a circular arc, the center of which is constant with the axis of the switch and the axis of the rotatable plate 28. The bimetal blades 31 and 32 are fixed to the plate 28, so that their contacts 66 and 66' are on the same circular arc as that of the contacts referred to above, and positioned so that the contacts 66 and 66' engage predetermined fixed contacts at a given rotated position of the plate 28.

While the plate 28 is shown as substantially dished with the bimetal blades 31 and 32 mounted thereon, this plate may be substantially a flat disc with its rim engaging the rim of the metal plate 56. In any case, sufficient space should be provided between these plates to accommodate movement of the bimetal blades 31 and 32, or at least the plate 28 should be arranged the necessary distance away from the contacts 47, 48, 49 and 52 to permit of this movement. With the plates arranged as shown in Fig. 5, the peripheral flanges engage each other and provide ample bearing surfaces which contribute to the ease of rotation of the plate 28. The flanges of the plates 28 and 56 are held in matching relation

to each other by the surrounding cylindrical portion 35 of the base member 22.

The modified form of switch shown in Figs. 14 to 24 is in many respects similar to the form of switch described above, particularly with respect to the switch casing and the use of three bimetal blades as circuit breakers. Referring to Figs. 14 to 17 and 21, it will be noted that this modified form of switch construction includes a metal cup-shaped cover 101 carrying an axially forwardly-extending bushing 102 threaded at its free end for receiving a nut by which the switch is mounted on or behind the vehicle dashboard or panel. The switch is operated by a shaft 103 extending through the bushing 102 and is staked to a metal driving member 104 inside the casing, such driving member being provided with end projections 105 and 106 of different widths for driving a rotatable switch member 107 of insulating material provided with matching slots 108 and 109 for respectively receiving the projections 105 and 106 of the driving member.

The front of the casing 101 includes radially-extending projections pressed out from the front 25 of the casing and forming detent slots 110 on the inside arranged to receive detent bosses 111 pressed out on the ends of the driving member 104. The switch has three positions determined by the three detent slots 110 on opposite sides of 30 the bushing 102. The peripheral portion of the cover 101 includes an enlarged cylindrical portion 112 at the back providing a shoulder upon which the peripheral edge of a base member 113 is adapted to rest and on which it is retained by bent-over tabs 112' carried by the cover.

The base member 113 is made up of insulating material including the annular projection which fits in the cylindrical portion 112 of the cover 101. The base member also includes a cylindrical wall section 114, as shown in Figs. 17 and 21. This wall section fits inside the cylindrical body of the cover 101 and its front edge faces the adjacent peripheral portion of the rotatable member 107. The inside portion of the base member 113 includes a substantially symmetrically arranged rectangular-shaped recess 115, in which is mounted a metal plate 116 having a backwardly-bent, forked end 117 (Fig. 21) engaged by the head 118 of a current supply terminal bolt 119 extending through the base 113 toward the back and tightly secured thereto by means of a nut 121 bearing on a metal washer 120. A second nut 122 is provided on the terminal bolt 119 for retaining a current lead to the battery of a car or other vehicle.

The metal plate 116, as shown in Fig. 21 extends forwardly at the top of the recess 115 and upwardly inside the base member to provide a contact sector 123 having the arcuate contour surface shown in Figs. 22, 23 and 24.

A bimetal circuit-breaker blade 124 is mounted in the recess 115 and riveted to the metal plate 116 by a rivet 125 extending through the body of the blade adjacent the end of the tongue of the blade, the back side of the end of the tongue carrying a contact 126 which normally engages a contact rivet 127 extending through the base member 113 and through a metal jumper plate 128 on the back of the base member to which the rivet is electrically connected.

The metal jumper plate 128 has the contour shown in Fig. 16 and is electrically connected by rivets 129 to three terminal receptacles A for electrical connection to accessories or auxiliary

electric equipment associated with the vehicle such as a radio, a heater, cigarette lighter, etc.

The various terminal receptacles shown in Fig. 16 for the various lighting and accessory circuits are all of the same construction as illustrated in Fig. 21, in which the rivet 129 is connected to one of the receptacles A comprising spring plates 130 and 131 extending through the back of the base 113 and forming a female terminal for receiving a rectangular-shaped male terminal which is attached to the connecting wire leading to a particular light fixture or accessory. The metal plate 131 is of spring metal and has a bent-over portion on the back of the base 113 extending over a portion of the opening in the base. Referring to Fig. 18, the remaining terminal receptacles at the back of the base member 113 include a receptacle H for the head lamp of the vehicle connected to a rivet 132 forming a contact 133 on the inside of the base, as shown in Fig. 20, a terminal receptacle P, for the parking lights of a vehicle connected to a rivet 134 which terminates in a contact 135 on the inside of the base member, this rivet also being connected by a metal jumper plate 136 and a rivet 137 to a terminal receptacle 145 for the lamp for an ignition key-operated switch, and terminal receptacles T and I respectively for the tail lights and the instrument lights of the vehicle connected by rivets 138 and 139 to a metal jumper plate 140, the rivets terminating respectively in contacts 141 and 142 (Fig. 20). The T and I receptacles are energized when either of the contacts 141 or 142 are engaged because of the connecting jumper plate 140.

All of the rivets in the base member 113 outside of the rectangular-shaped recess 115, with the exception of the rivets forming contacts 133, 135, 141 and 142, are recessed in the inside surface of the base member and covered by a spacer disc 143 of insulating material shown in Figs. 20 and 21, this disc having a rectangular recess matching the recess 115 and having round holes accommodating said contacts which are flush with the front surface of the disc. The spacer disc 143 extends under the contact sector 123, as shown in Fig. 21. The contacts 133, 135, 141 and 142 are arranged in spaced relation on a circular arc concentric with the base member so that they may be selectively engaged by a pair of contacts carried by the rotatable switch member 107.

The rotatable switch member 107 shown in Figs. 17, 18, 19 and 21 comprises a disc of insulating material having a peripheral edge portion 144 (Fig. 21) loosely fitting inside the cover or casing 101 and facing and slightly spaced from the front peripheral edge of the cylindrical wall 114. A portion of the body of the member 107 fits slightly inside the wall 114, as shown in Fig. 21, except for a pair of angularly-spaced stops 145 and 146 which operate in recesses 147 and 148 respectively in the front edge of the cylindrical wall 114, such recesses being separated by a portion of this wall forming a stop 149 (Figs. 21 to 24).

The back face of the member 107 includes a metal conductor plate 150 having a rearwardly-bent arm portion carrying a backwardly-facing contact 151 engaging the contact plate 123, as shown in Fig. 21. The plate 150 is riveted to the member 107 by means of a pair of rivets 152 which also serve to mount on the plate a pair of bimetal blades 153 and 154. The rivets 152 extend through the blades opposite the end of their tongues fix, and electrically connect the

blades to the plate 150. The ends of the tongues of the blades 153 and 154 carry contacts 155 on their under side which respectively engage the heads of contact rivets 156 (Fig. 18) extending through the member 107 and respectively connected to the ends of metal jumper plates 157 and 158 mounted on the front of the member 107. The opposite ends of these jumper plates are electrically connected to retaining rivets extending through the member 107 and having contact heads 159 and 160, respectively projecting from the back of the member 107 to approximately the level of the contact 151, as indicated in Fig. 21. When the member 107 is assembled in the position shown in Fig. 21, the contact 151 is adapted to operate on the contact plate 123, while the contact 159 is adapted to engage contacts 141 and 142 and contact 160 is adapted to engage contacts 133 and 135.

In assembling the elements of the switch shown in Figs. 14 to 17 and 21, the member 107 is arranged in its proper position with respect to the member 113 by having the stops 145 and 146 on the opposite sides of the stop 149. The members 105 and 106 of the driver 104 are inserted respectively in slots 108 and 109, after inserting a compression spring 161 in a recess 162 in the front of the member 107. The end of the shaft 163 is then inserted in bushing 102 and the four assembled elements to the right in Fig. 17 are inserted as a body in the casing 101 with the indentation 165 in the rim of the member 113 rotated to a position where it fits around the pressed-in portion 164 (Fig. 16) in the rim 112 of the casing 101.

When the elements of the switch are pressed tightly together, the tabs 112' are bent over around the peripheral edge of the back portion 113 in the manner shown in Fig. 21. In this position, the spring 161 will be under compression, as shown in Fig. 21 and thereby insure firm engagement between the contact 151 and the plate 123, and the contacts 159 and 160 with their co-operating contacts in the base member 113. The member 107 includes on its forward surface projections 163 respectively on opposite sides of the recess 162 for preventing engagement of the metal driving member 104 with either of the metal jumper plates 157 and 158. The elements of the switch shown in Figs. 1 to 13 are assembled and oriented with respect to each other in the same manner.

The switch shown in Figs. 14 to 24 has three operative positions corresponding to the three detent recesses 110 on opposite sides of the axis of the front of the casing 101. The relative positions of the members 107 and 113 for these three positions are shown in Figs. 22, 23 and 24, in which the stops 145 and 146, the contacts 151, 159 and 160, and the driving projections 105 and 106 of the member 107 are all shown in section. Fig. 24 shows the switch with the rotatable member 107 rotated as far as possible counterclockwise to the "off" position with the stop 146 engaging the stop 149. In this position, the contact 151 engages the plate 123 but the contacts 159 and 160 are in engagement with the spacer disc 143.

The first "on" position of the switch is obtained by rotating member 107 one step clockwise, the stop 146 being moved away from the stop 149, as shown in Fig. 22, at which position the contacts 159 and 160 respectively engage the contacts 142 and 135 so that circuits will be completed between battery and terminal P, battery and

terminal 10, battery and terminal T, and battery and terminal I.

In the second clockwise "on" position of the switch, as shown in Fig. 23, the stop 145 engages the stop 149, so that contacts 159 and 160 engage contacts 141 and 133 respectively. In all positions of the switch, the contact 151 remains in engagement with the metal contact sector 123. In this second "on" position, circuits are completed between battery and H, battery and T, and battery and I. In other words, the head and tail lamps of the vehicle are energized as well as the instrument lamps.

The circuits through the three terminal receptacles A are not affected by the rotation of the member 107, since these circuits are connected directly to the terminal post 119 through the bimetal circuit breaker blade 124. If either of these circuits should become overheated, this bimetal blade will become heated also and break connection between contacts 126 and 127, thereby providing protection for all three of these circuits and the devices associated therewith. Separate bimetal blades may be provided in the base member for the accessory terminals A, and two or more of such blades and terminals may be provided. The bimetal circuit breaker blades 153 and 154 protect the circuits connected by contacts 159 and 160 in a similar manner. These bimetal blades as well as the bimetal blade or blades 124 have a construction similar to that indicated in Fig. 8 for the blades 31 and 32, and have the same function.

The switch illustrated in Figs. 1 to 13 provides a construction in which all of the lighting and other circuits of the vehicle are protected individually or in groups by the bimetal blades 31, 32 and 58. In the modified construction shown in Figs. 14 to 24, all of the circuits are protected in the same way by bimetal circuit breakers, the three circuit breakers being arranged in parallel and two of them, as in the switch of Figs. 1 to 13, are carried by a rotatable switch member for protecting different circuits or groups of circuits connected-up through the output terminals on rotation of the rotatable switch member to different "on" positions.

While two or more bimetal blades are preferably mounted on the rotatable switch member, it is to be understood that instead of providing two or a plurality of circuit breakers on the rotatable switch members, a single circuit breaker may be provided thereon and two or more circuit breakers may be mounted in parallel fixed positions on the fixed base member of the switch. In such a construction, the bimetal circuit breaker mounted on the rotatable member may be arranged for parallel connection with the others, and means provided on the rotatable member for selectively closing a circuit through one or both of the circuit breakers carried in fixed position on the base member.

With respect to the modified form of construction shown in Figs. 14 to 21, the arrangement of parts may be reversed with respect to the fixed base member 113 and the rotatable member 107. In other words, the rotatable member may carry one circuit breaker, connectable to one or more light circuits by rotation to two or more "on" positions, while the base member may carry a pair of circuit breakers, one being connected directly in the accessory circuit or circuits and the other being connectable through the rotatable member to one or more light circuits when the rotatable member is rotated from

"off" to one or more "on" positions. Other modifications may be made in the construction and arrangement of the parts of the switch without departing from the scope of the invention, as defined in the appended claims.

While the rotary switch of the present invention is particularly adapted for controlling and protecting the lighting and other circuits of a motor vehicle, it may be used to advantage for other purposes.

What I claim is:

1. A rotary electric switch including a base member of insulating material, a plurality of current outlet terminals and a current supply terminal connected into the back of the base member, a contact mounted on the front of said base member for each of at least some of said outlet terminals and connected thereto, a metal plate mounted in the front of said base member out of direct contact with any of said contacts, said current supply terminal being electrically connected to said metal plate, a bimetal blade electrically connected in fixed position to said metal plate and having a movable contact normally engaging one of said contacts connected to an outlet terminal, said metal plate being fixed to said base member, a rotatable switch member mounted over said fixed metal plate and having an electrical connection thereto, a plurality of bimetal blades fixed to the back of said rotatable member each having a movable contact, means for electrically connecting the contacts of said plurality of bimetal blades to selected ones of the other contacts on the front of the base member upon rotation of the rotatable switch member, and means for driving said rotatable switch member to effect its rotation, each of said bimetal blades being deflectable to disengage its movable contact when the current load conducted by the bimetal blade exceeds a predetermined value.

2. A rotary electric switch as claimed in claim 1, in which the rotatable metal plate is circular and rotatable on its axis, the plurality of contacts except for the contact under the fixed metal plate arranged in an arc concentric with respect to the axis of the rotatable plate, and the movable contacts of the plurality of bimetal blades being arranged in the same arc as that of said plurality of contacts.

3. A rotary electric switch as claimed in claim 2, in which the fixed metal plate includes a pair of spaced contact projections having surfaces in the same plane and in the same arc as those of said plurality of contacts, said contact projections being adapted for engagement by the movable contacts of two bimetallic blades of said plurality of blades when the switch is in the "off" position.

4. An electric switch including a base member of insulating material, a plurality of electric current output terminals and a current supply terminal connected into the back of the base member, a contact at the front of said base member for each of at least some of said current outlet terminals and connected thereto, a rotatable switch member mounted for rotation in front of the base member, a bimetal blade mounted in fixed position with respect to the base member and having a movable contact normally engaging one of said contacts connected to one of said output terminals, a plurality of bimetal blades mounted between said members one at least of which is fixed to the back of said rotatable member, each of said plurality of blades having a

movable contact, means for electrically connecting the movable contacts of said plurality of bimetal blades to selected ones of the other contacts at the front of the base member upon rotation of the rotatable switch member, means providing an electrical connection from said current supply terminal to said fixed bimetal blade and said plurality of bimetal blades, and means for driving said rotatable switch member to effect its rotation, each of said bimetal blades being deflectable to disengage its movable contact when the current load conducted by the bimetal blade exceeds a predetermined value.

5. An electric switch including a base member of insulating material, a plurality of electric output terminals connected into the back of the base member, contacts at the front of said base member electrically connected to said terminals, a rotatable switch member mounted for rotation in front of the base member, a current supply terminal connected into the back of the base member, a bimetal circuit breaker blade mounted in fixed position with respect to the base member and having a movable contact normally engaging one of said contacts, means carried by said rotatable member including a plurality of contacts arranged to cooperate with the other contacts of the base member to provide a plurality of circuits when the rotatable switch member is rotated, a bimetal circuit breaker blade arranged in each of said circuits at least one blade of which is fixed to said rotatable member, means for electrically connecting each of said bimetal circuit breaker blades to said current supply terminal, and means for driving said rotatable switch member to effect its rotation, each of said bimetal blades being deflectable to break the circuit protected thereby when the current load conducted by the bimetal blade exceeds a predetermined value.

6. A rotary electric switch including a base member of insulating material, a plurality of current output terminals mounted on the back of the base member, a contact mounted on the front of said base member for each terminal and connected thereto, a metal plate mounted on the front of said base member over one of said contacts in spaced relation thereto, a bimetal blade electrically connected in fixed position on the back of said metal plate and having a movable contact normally engaging the contact over which said plate is mounted, said metal plate being fixed to said base member, a current supply terminal connected into the back of said base member and electrically connected to said metal plate, a rotatable metal plate mounted over said fixed metal plate and electrically connected thereto, a plurality of bimetal blades fixed to the back of said rotatable metal plate each having a movable contact normally biased toward the front of the base member, the contacts of said plurality of bimetal blades being arranged to engage selected ones of the contacts mounted on the front of the base member upon rotation of the rotatable metal plate, and means for driving said rotatable metal plate to effect its rotation, each of said bimetal blades being deflectable to disengage its movable contact when the current load conducted by the bimetal blade exceeds a predetermined value.

7. A rotary electric switch as claimed in claim 6, in which the means for driving the rotatable metal plate comprises a disc of insulating material having a surface engaging the front surface of the rotatable plate, and means for keying the

disc to the rotatable plate to prevent relative rotation.

8. A rotary electric switch as claimed in claim 6, in which the means for driving the rotatable metal plate includes a disc of insulating material keyed thereto, a driving plate engaging said disc, and a shaft fixed to the driving plate.

9. A rotary electric switch including a cylindrical base member of insulating material having a back wall, a plurality of current outlet terminals mounted on the back of said wall, a contact mounted on the front of said wall for each terminal and connected thereto, said contacts being within the cylindrical portion of the base, a circular-shaped metal plate mounted on the front of said base member and fixed thereto over one of said contacts and in spaced relation to the contact, a bimetal blade electrically connected in fixed position on the back of said metal plate and having a movable contact normally engaging the contact over which said plate is mounted, said metal plate having openings through which the remaining contacts extend in spaced relation, a current supply terminal connected into the back of the base member and electrically connected to said metal plate, a circular-shaped rotatable metal plate mounted over said fixed metal plate, said metal plates engaging each other rim-to-rim within the cylindrical portion of the base member, a plurality of bimetal blades fixed to the back of said rotatable metal plate each having a movable contact normally biased toward the front of the base member, the contacts of said plurality of bimetal blades being arranged to engage selected ones of the contacts mounted on the front of the base member upon rotation of the rotatable metal plate, and means for driving said rotatable metal plate to effect its rotation, each of said bimetal blades being deflectable to disengage its movable contact when the current load conducted by the bimetal blade exceeds a predetermined value.

10. A rotary electric switch as claimed in claim 9, in which said remaining contacts are arranged in an arc concentric with the axis of said rotatable metal plate, and in which the movable contacts of the plurality of bimetal blades are arranged in the same arc as said remaining contacts.

11. A rotary electric switch as claimed in claim 10, including a pair of spaced contact projections on said fixed metal plate arranged in the arc of said remaining contacts, said contact projections having contact surfaces in the same plane as that of the surfaces of said remaining contacts, said contact projections being arranged for engagement by movable contacts of the plurality of bimetal blades when the switch is in its "off" position.

12. A rotary electric switch including a base member of insulating material, a plurality of output terminals extending into the back of the base member, a contact at the front of said base member for each of at least some of said terminals and connected respectively thereto, a current supply terminal connected into the back of said base member, a bimetal blade electrically connected to said supply terminal mounted in fixed position with respect to the base member and having a movable contact normally engaging one of said contacts, a rotatable switch member mounted for rotation in front of said base member, a plurality of bimetal blades fixed to the back of said rotatable member each having a movable contact and being electrically con-

nected to said current supply terminal, means for electrically connecting the contacts of said plurality of bimetal blades to selected ones of the other contacts at the front of the base member upon rotation of the rotatable switch member, and means for driving said rotatable switch member to effect its rotation, each of said bimetal blades being deflectable to disengage its movable contact when the current load conducted by the bimetal blade exceeds a predetermined value.

13. A rotary electric switch as claimed in claim 12, including a metal contact plate at the front of the base member electrically connected to the current supply terminal, and electrical connector means connected to the bimetal blades mounted on the rotatable member including a contact engaging said contact plate for electrically connecting the said bimetal blades to the current supply terminal.

14. A rotary electric switch as claimed in claim 13, in which the bimetal blade mounted in fixed position with respect to the base member is fixed to said contact plate.

15. A rotary electric switch as claimed in claim 12, in which the means for electrically connecting the movable contacts of said plurality of bimetal blades to selected ones of the other contacts on the front of the base member comprises a contact on the back of the rotatable member for each of said plurality of bimetal blades and electrically connected to the movable contact thereof.

16. A rotary electric switch as claimed in claim 12, in which each output terminal comprises a pair of metal plates mounted in a recess in the back of the base member, one of which is of spring metal and is biased toward the other plate of the terminal.

17. A rotary electric switch as claimed in claim 12, having an "off" position and first and second "on" positions, stop means on the base member and a pair of stop means on the rotatable member cooperating on opposite sides of said first-mentioned stop means, one of the stop means on the rotatable member engaging the stop means on the base member when the rotatable member is in the "off" position of the switch, and means for rotating the rotatable member to a first "on" position and a second "on" position for the switch, said second stop member on the rotatable member being in engagement with the stop member on the base member when the switch is in its second "on" position.

18. A rotary electric switch including a cylindrical base member of insulating material, a plurality of current output terminals extending into the back of the base member, a contact at the front of said base member for each of at least some of said terminals and connected respectively thereto, said contacts being arranged in an arc about the axis of the base member, a current supply terminal connected into the back of said base member, a metal contact plate at the front of the base member angularly spaced with respect to said contacts, and connected to said current supply terminal, a bimetal blade electrically connected to and mounted in fixed position on a portion of said metal contact plate inwardly of its peripheral portion and having a movable contact facing toward the back of the switch, a fixed contact connected to at least one of said output terminals and normally engaged by said movable contact, a rotatable switch member of insulating material mounted for rotation in front of said base member, a metal plate fixed to the back of said rotatable member and having a contact engaging said contact plate, a plurality of bimetal blades fixed to the back of said metal plate on said rotatable member each having a movable contact facing toward the front of the switch, fixed contacts respectively engaged by the movable contacts of said plurality of bimetal blades, fixed contacts on the back of said rotatable member respectively electrically connected to said fixed contacts engaged by the movable contacts of said plurality of bimetal blades, said fixed contacts on the back of said rotatable member being positioned to respectively engage selected ones of the plurality of contacts at the front of the base member upon rotation of the rotatable switch member to selected positions, and means for driving said rotatable switch member to effect its rotation, each of said bimetal blades being deflectable to disengage its movable contact when the current load conducted by the bimetal blade exceeds a predetermined value.
